SNUBBED TRUCK

Fred E. Bachman and Albert F. Seelig, Jr., St. Louis, Mo., assignors to American Steel Foundries, Chicago, Ill., a corporation of New Jersey

Application August 8, 1956, Serial No. 602,710

11 Claims. (Cl. 105—197)

The present invention relates to snubbed trucks for 15 railway freight cars.

An object of the invention is to provide novel means for controlling the vertical movement of the load carrying springs of a railway freight car.

Another object is to provide snubbing means embodying spring means of rubber-like material, arranged so as to produce snubbing effect in proportion to the load imposed on the car.

A further object is to provide snubbing means of the foregoing general character, that is, of unusually simple and rugged construction.

Other objects and advantages of the invention will appear from the following detail description taken in conjunction with the accompanying drawing, in which:

Figure 1 is a side view of a portion of a railway car truck embodying the present invention, with portions shown in section;

Figure 2 is a sectional view taken on line 2—2 of Figure 1, and

Figure 3 is an exploded perspective view of the snubbing means constituting the subject matter of the invention included in Figure 1.

Referring now in detail to the drawing, the construction embodying the invention is incorporated in a side frame indicated generally at 12 which includes conventional construction elements, such as a compression member 14, tension member 16, and side columns 18 defining a bolster opening 20 therebetween. A bolster 22 is mounted in said opening on load carrying springs 24 in a conventional manner and as is well known, the bolster moves or vibrates in a vertical plane. The movement of the bolster includes a vertical component and a transverse component i.e., the movement is in a plane transverse to the side frame so that the transverse movement mentioned is in a direction longitudinally of the bolster. For convenience in representation, Figure 1 shows a first portion 22a of the bolster in the position assumed in the case of a light car and another portion 22b in the position it assumes in the case of a loaded car.

The bolster 22, as seen in Figure 2, includes flanges or fork elements 26 spaced longitudinally along the bolster and telescoping a portion 27 of the column 18 of the side frame. These flanges afford limiting means for transverse movement of the bolster by engaging the side portions of the side frame column. It will be understood that the bolster has such flanges 26 at each of opposite sides for receiving the respective side frame columns. Between the flanges is a recess 28 at each side of the bolster which includes an inclined friction surface 30 (Figures 1 and 2) at the floor of the recess, i.e., it extends transversely between the flanges.

Referring particularly to Figure 1, it will be observed that the inclined friction surface 30 faces generally in the direction of the corresponding column 18. The latter has a vertical planar surface 32 on which is supported a wear plate 34 in a suitable manner, the wear plate 34 defining a vertical friction surface 35 engaging a snubbing

device 36 which cooperates with the inclined friction surface 30 to snub vertical movement of the bolster relative to the side frame. Between and engaging these two friction surfaces is the snubbing means 36 constituting the present invention. The snubbing means 36 is shown in its entirety in Figure 3 and includes a spring element 38 and a shoe or cap 40. As best seen in Figure 1, engagement of the cap 40 with the wear plate 34 affords lateral support for the snubbing means 36 along an area 10 of the wear plate 34 which faces and is in horizontal alignment with the inclined bolster surface 30. Thus, the snubbing means 36 function to support a part of the bolster load and to this extent may be regarded as bolster supporting spring means auxiliary to the springs 24. The spring member 38 is of rubber or rubber-like material. As such, it is yieldable in all directions uniformly. Any of various known kinds of rubber, or rubber-like material having yieldable characteristics similar to those of rubber, may be utilized. The cap 40 is of rigid material, such as steel.

The spring element 38 includes a body portion or column 42 which is disposed vertically when assembled in place. On the bottom surface of the column portion is a projection or button 44 (Figure 1) received in an aperture 46 in an element 48 of the side frame. In the upper end of the spring element 38 are side grooves 50 (Figure 2) disposed at an acute angle to the longitudinal axis of the spring member, defining a face portion 52 inclined at an angle similar to that of the grooves and extending generally laterally from the projection of the body portion 42.

The shoe or cap 40 is shaped to fit over the upper end of the body portion 42 of the spring member, being of appropriately tapered shape for the purpose, and it includes a side opening 54 between ribs 56. The cap is fitted over the spring member with the ribs 56 fitted in the grooves 50, as shown best in Figure 1, and in this relation of the parts, the face portion 52 is exposed outwardly of the shoe.

It will be seen that one such spring means is disposed at each side of the bolster. Referring to the left portion of Figure 1, the snubbing means 36 is interposed between the bolster and side frame. The lower end of the body portion 42 is vertically supported on the element 48 of the side frame and the projection 44 is disposed in the aperture 46 as mentioned above. The upper end portion of the snubbing means 36 is interposed or wedged between the friction surfaces 30 and 35. The inclination of the face portion 52 is the same as or similar to that of the friction surface 30 and engages the latter. The surface 58 of the shoe opposite that of the inclined ribs 56 engages the friction surface 35 of wear plate 34, being vertically disposed for that purpose.

The spring element in the uppermost position of the bolster is confined in compression between the surface 30, wear plate 34 and frame element 48. Upon downward movement of the bolster, the spring element 38 is compressed in a downward direction (i.e. principally so, although it may be compressed in other directions also) to or toward the position indicated at the right hand portion of Figure 1. The spring element is shortened in vertical direction and the shoe or cap 40 moves vertically, the surface 58 sliding on the wear plate 34 in friction engagement therewith.

Such downward movement of the bolster and consequent further compression of the spring element results in increased resistance proportional to the downward movement of the bolster. There may be sliding movement between the face portion 52 and friction surface 30 of the bolster although this sliding movement is minor. The friction between the latter two elements is quite great; the adhesion of the resilient member playing a

large part in such resistance. Most of the sliding effect takes place between the surface 58 opposite thereto and the wear plate 34, these two elements being of rigid material. Furthermore, they are vertically disposed and thus in the plane of movement of the bolster.

The three points of engagement of the snubbing means, namely at the element 48, friction surface 30 and friction surface 35, define a direct force path having portions distributed in an arc of at least 180° and preferably greater than that extent.

The greater portion of the snubbing action of the snubbing means 36 is in downward movement of the bolster, but there is substantial snubbing action in upward movement thereof since the compression of the spring element is not completely lost, and hence the friction between the shoe or cap 40 and the wear plate 34 remain at a substantial value. For this reason also snubbing action is accomplished in transverse direction.

The rubber or rubber-like spring member 38 is universally compressible and provides a hysteresis effect resulting in greater effect in snubbing harmonic vibrations of the bolster supporting springs 24.

The snubbing means 36 at opposite sides of the bolster are, of course, effective for damping vibrations in directions longitudinally of the side frame.

We claim:

1. In a railway car truck, a side frame having spaced columns defining a bolster opening, a bolster spring-supported in said opening and movable vertically therein, and spring means operatively interposed between said bolster and side frame and including a rubber-like element having support at its lower end on the side frame, and having its upper end wedged between a vertical surface on the side frame and an inclined surface on the bolster disposed in upwardly converging relation to the vertical surface, said spring means including a rigid cap on the upper end of said rubber-like element and interposed between the latter and said vertical surface and slidable on said vertical surface.

2. In a railway car truck, a side frame having spaced columns defining a bolster opening, a bolster spring-supported in said opening and movable vertically therein, and spring means operatively interposed between said bolster and side frame and including a rubber-like element having support at its lower end on the side frame, and having its upper end wedged between a vertical surface on the side frame and an inclined surface on the bolster disposed in upwardly converging relation to the vertical surface, said spring means including a rigid cap on the upper end of said rubber-like element and interposed between the latter and said vertical surface and slidable on said surface, the rubber-like element having a portion exposed through said cap and engaged with said inclined surface.

3. In a railway car truck, a side frame having spaced columns defining a bolster opening, a bolster spring-supported in said opening and movable vertically therein, and spring means operatively interposed between said bolster and side frame and including a rubber-like element having support at its lower end on the side frame, and having its upper end wedged between a vertical surface on the side frame and an inclined surface on the bolster disposed in upwardly converging relation to the vertical surface, said spring means also including a rigid upwardly tapering cap on the upper end of the rubber-like element confining three sides of the latter and forming the portion of the spring means engaged with said vertical surface and being slidable on the latter, the fourth side of the cap having an opening and ribs at the sides of the opening disposed in grooves in a portion of the rubber-like opening projected through the opening, the projected portion of the rubber-like element having a generally flat surface engaged with said inclined surface on the bolster.

4. A truck comprising a side frame having spaced col-

umns defining a bolster opening, a bolster spring-supported in said opening and movable vertically therein, said columns having interfacing vertical surfaces and the bolster having a surface at each side inclined upwardly and toward the corresponding vertical surface, and spring means at each side of the bolster, each spring means including a rubber-like element, said element engaging said inclined surface on the bolster, and a rigid cap carried by the element and interposed between the bolster and the side frame, said cap and element contacting two areas on the side frame, the three areas of engagement defining a direct force path having portions distributed in an arc of at least 180°.

5. A truck comprising a side frame having spaced columns defining a bolster opening, said columns having interfacing vertical friction surfaces, a bolster spring-supported in said opening and movable in a vertical plane transverse to the side frame, said bolster having a recess on each side facing said columns and flange elements on opposite sides of each recess engageable with opposite sides of the side frame for limiting movement of the bolster transversely of the frame, said bolster having an inclined surface on each side in the corresponding recess and facing the corresponding vertical surface, and spring means at each side of the bolster including a rubber-like spring element and a rigid cap on the upper end thereof, the spring means having vertical support in the side frame and having its upper end wedged between said inclined and vertical surfaces, said cap being disposed in said recess and confined thereby in directions transversely of the side frame.

6. A railway car truck comprising a side frame member having a friction surface, a shoe member engaged therewith, a bolster member supported by the side frame member, and a resilient mass engaging all said members, the bolster member being spaced from the shoe member by said mass.

7. A railway car truck comprising a side frame, a bolster spring-supported by the side frame and having an inclined side surface, and snubbing means including a resilient mass directly engaging said inclined side surface and a side frame portion therebelow, said snubbing means comprising means slidably engaging another side frame portion which faces and is in horizontal alignment with said inclined surface.

8. A railway car truck comprising a side frame having a vertical friction surface, a shoe having a friction surface engaged with the friction surface on the side frame, a bolster structure spring-supported by the side frame and having an inclined side surface, and a resilient mass compressed between the shoe, the inclined surface and another point on the side frame.

9. A railway car truck comprising a side frame having a column partly defining a bolster opening, said column having a friction surface, a bolster structure movably supported by said frame, friction shoe means carried by the side frame and engageable with said vertical surfaces, said shoe means comprising a resilient mass having vertical support from the side frame, said mass having its upper end wedged between said vertical surface and bolster, a shoe carried by the upper end of said mass, a portion of said mass being disposed without the shoe, and an inclined surface on said bolster, said shoe being engageable with said vertical surface, said portion being engageable with said inclined surface.

10. A railway truck, a side frame having spaced columns defining a bolster opening, a bolster spring-supported in said opening and movable vertically therein, and spring means operatively interposed between said bolster and side frame and including a rubber-like element having support at its lower end on the side frame, said element having its upper end wedged between a vertical surface on the side frame and an inclined surface on the bolster disposed in upwardly converging

relation to the vertical surface, said spring means including a rigid cap on the upper end of said rubber-like element and interposed between the latter and said vertical surface and slideable on said vertical surface, the rubber-like element having a portion exposed through said cap and engaged with said inclined surface, said portion being inclined at an angle similar to the angle of the inclined surface, said element comprising grooves, said cap having ribs disposed within said grooves, said grooves and ribs being disposed at an angle similar to the angle of the inclined surface.

11. In a railway car truck, a side frame having spaced columns defining a bolster opening, a bolster spring-supported in said opening and movable vertically therein,

5
10

and snubbing means operatively interposed between said bolster and side frame and including a rubber-like element, said rubber-like element having support at its lower end on the side frame, said snubbing means having lateral support on a side frame column surface, said rubber-like element bearing against an inclined surface on the bolster disposed in upwardly converging relation to the column surface.
